UNITED STATES PATENT OFFICE

JAMES W. HARLE, JR., OF CLEARWATER, FLORIDA

DESIGN FOR A MOTOR-VEHICLE RADIATOR STATUETTE OR SIMILAR ARTICLE

Application filed April 26, 1930. Serial No. 35,398. Term of patent 7 years.

To all whom it may concern:

Be it known that I, JAMES W. HARLE, Jr., a citizen of the United States, residing at Clearwater, in the county of Pinellas and State of Florida, have invented a new, original, and ornamental Design for a Motor-Vehicle Radiator Statuette or Similar Article, of which the following is a specification, reference being had to the accompanying drawing, forming part thereof.

The figure is a perspective view of a motor vehicle radiator statuette constructed in accordance with my design.

I claim:

The ornamental design for a motor vehicle radiator statuette or similar article, as shown.

JAMES W. HARLE, JR.
